Patented Feb. 1, 1916.

Application filed March 3, 1915. Serial No. 11,869. Term of patent 3½ years.

To all whom it may concern:

Be it known that I, VICTOR E. BLOM, a citizen of the United States, and resident of the borough of Brooklyn, county of Kings, city and State of New York, have invented a new, original, and ornamental Design for a Vest or Similar Article, of which the following is a specification, reference being had to the accompanying drawing, forming part thereof.

The figure is an elevation or front view of a vest showing my new design therefor.

The design comprises a representation of the lower portion of a vest, upon which the

buttons and pockets are represented. The central portion is made to appear to overlap and the upper edge, at its central portion, is curved to represent a dress vest. The ends are narrowed down to projecting strips upon which the fastening means are shown.

I claim:—
